[57] CLAIM

The ornamental design for an amphibious all terrain vehicle, as shown and described.

DESCRIPTION

FIG. 1 is a perspective view of an amphibious all terrain vehicle showing my new design;

FIG. 2 is an enlarged left side elevational view thereof;

FIG. 3 is an enlarged right side elevational view thereof;

FIG. 4 is an enlarged top plan view thereof;

FIG. 5 is an enlarged bottom plan view thereof;

FIG. 6 is an enlarged front elevational view thereof; and,

FIG. 7 is an enlarged rear elevational view thereof.

The broken line showing of environment is for illustrative purposes only and forms no part of the claimed design.
